Attorney

UNITED STATES PATENT OFFICE.

GROVER C. HENDRICKS, OF DUGGER, INDIANA.

CARBID-LAMP.

1,331,430.

Specification of Letters Patent. Patented Feb. 17, 1920.

Application filed April 16, 1917. Serial No. 162,452.

To all whom it may concern:

Be it known that I, GROVER C. HENDRICKS, a citizen of the United States, and resident of Dugger, in the county of Sullivan 5 and State of Indiana, have invented certain new and useful Improvements in Carbide Lamps, of which the following is a specification.

This invention relates to improvements in 10 carbide lamps and the invention has for its dominant object to provide a carbide lamp in which the coöperating gas generating parts are arranged within a supporting base, thus protecting the same and also affording an 15 extremely compact and ornamental construction.

Another object of the invention is to provide novel water discharge means for supplying water to the carbide chamber of the 20 lamp construction.

Other and further improvements and novel details in the construction and arrangement of parts will be appreciated from the description to follow, which, for a clear 25 understanding of the invention should be considered in connection with the accompanying drawings forming a part hereof and wherein the preferred embodiment of the invention is shown for the purpose of 30 illustration.

In the drawings:

Figure 1 is a vertical section through the improved carbide lamp, and

Fig. 2 is a horizontal section therethrough 35 taken on the line 2—2 of Fig. 1.

Similar characters of reference are employed in all of the above described views to indicate corresponding parts.

Referring now more specifically to the 40 several figures of the said drawings, a hollow supporting base 1 is provided the lower portion of which is formed to constitute a pedestal or stand 2, while the upper portion thereof, as will be noted in the Fig. 1, is 45 open.

A water containing receptacle 3 is provided and has the upper portion thereof formed with a laterally extending annular lip 4 adapted to be engaged with the upper 50 marginal edge of the supporting base 1 in order that the said receptacle 3 may be efficiently supported therein. A filling opening is formed within the top of the water receptacle 3 and is normally closed by means 55 of a screw cap 5 turned into engagement

therewith. To permit the flow of water from the receptacle 3 a neck 6 is engaged with the bottom thereof and has its free extremity braced by means of a metal strap 7 arranged thereabout. A valve stem 8 is 60 passed downwardly through the water receptacle 3 and carries a valve 8^a at its lower end which is adapted to be arranged over the open end of the said neck, at times, for an obvious purpose. To render the receptacle 65 fluid tight, a packing gland 9 is arranged within the receptacle bottom and receives the said valve 8 therethrough.

A gas discharge conduit 10 extends through the water receptacle 3 and opens 70 onto the bottom thereof to permit the discharge of gas from the generating chamber into the same from where it is conveyed to the burner 11 arranged upon the upper end thereof. Filtering material 12 may be and 75 preferably is arranged adjacent the open lower end of the conduit 10.

Upon the under face of the water receptacle bottom there is arranged an internally screw threaded collar 13 adapted to 80 receive therein a similarly threaded collar 14 formed upon a lid member 15 which turns into engagement with the open upper extremity of a carbide receptacle 16.

The usual chimney holder 17 is arranged 85 upon the top portion of the water receptacle 3 about the burner 11 and carries thereon springs in the engaging fingers 18.

In operation, the carbide receptacle 16 is filled and engaged with the screw threaded 90 collar 13 of the water receptacle 3 thereupon the said receptacles are placed within the hollow supporting base 1, the annular-lip 4 engaging with the upper marginal edge of the said base and serving to support the 95 same in proper position thereupon. By regulating the valve 8, water will be permitted to flow from the discharge neck 6 into the carbide receptacle 16 and as a result, gas will be generated and conveyed by the conduit 10 to the burner 11 whereat it is ignited.

This assembling of the coöperating parts of the gas generating apparatus of the lamp will be readily permitted due to their positioning within the hollow supporting base 1. Further, repairing to any part thereof can be readily done.

It is to be understood that the lamp is not to be limited in its use by slight variations 110

in the construction thereof and can be used as a hand lantern, vehicle lantern, mining lamp, house lamp, etc., such as conditions or preference may dictate.

5 Manifestly the construction shown is capable of considerable modification and such modification as is within the scope of my claims I consider within the spirit of my invention.

10 I claim:—

1. In a carbid lamp, detachably connected superposed water and carbid receptacles, a gas discharge conduit extending through the water receptacle and communicating with 15 the interior of the carbid receptacle, a water supply pipe communicating with the water receptacle and extending into the carbid receptacle and provided with an upwardly directed discharge terminal arranged in the 20 upper portion of the carbid receptacle, a valve stem adjustably fitted in the upper part of the water receptacle and extending through the lower portion thereof, a fluid-tight joint receiving the lower portion of 25 the valve stem extended through the bottom of the water receptacle, and a flat disk-like valve carried by the lower terminal of the stem engageable with the discharge terminal

of the water pipe to control the flow of water therethrough.

2. In a carbid lamp, detachably connected and superposed water and carbid receptacles, a gas discharge conduit arranged in the water receptacle and communicating with the carbid receptacle, a water pipe communicating with the water receptacle, extending into the carbid receptacle and having an upwardly directed discharge terminal arranged in the upper portion of the carbid receptacle, a valve stem adjustably fitted in the upper portion of the water receptacle, a fluid-tight gland rotatably receiving the portion of the stem extending through the bottom of the water receptacle, a valve carried by the lower terminal of the stem engageable with the discharge terminal of the pipe, said valve being of flat disk-like form and adapted to be rotated against the terminal of the pipe to reduce carbid deposits thereon and secure a snug fit of the valve upon the terminal of the pipe, and a brace arranged to withstand the pressure exerted by the valve upon the terminal of the water pipe.

30 35 40 45 50 In testimony whereof, I affix my signature hereto.

GROVER C. HENDRICKS.
